UNITED STATES PATENT OFFICE.

WILLIAM M. SMITH, OF WEST MERIDEN, CONN., ASSIGNOR TO THE MERIDEN BRITANNIA COMPANY, OF SAME PLACE.

DESIGN FOR A COFFIN-PLATE.

SPECIFICATION forming part of Design No. 11,945, dated August 17, 1880.

Application filed July 21, 1880. Term of patent 14 years.

To all whom it may concern:

Be it known that I, WM. M. SMITH, of West Meriden, in the county of New Haven and State of Connecticut, have invented a new Improvement in Coffin-Plates; and I do hereby declare the following, when taken in connection with the accompanying drawing, to be a full, clear, and exact description of the same, and which said drawing constitutes part of this specification, and represents a face view.

This invention relates to a design for the name-plate used upon coffins; and it consists in the configuration and ornamentation, as shown in the accompanying illustration.

The plate is oblong in shape. Its two sides are of corresponding ogee shape, its two ends

straight and parallel, the ends ornamented with the representation of fringe. Around the edge of the plate is a molding ornamented with a scallop-shaped tracery, as shown in the accompanying illustration.

I claim—

The design for coffin-plate, consisting of the oblong plate, its ends parallel, and sides of ogee shape, with a molding around its edge of scallop-shaped tracery, and on its ends the representation of fringe, as shown in the accompanying illustration.

WILLIAM M. SMITH.
